UNITED STATES PATENT OFFICE

ABRAM K. BAER, OF BALTIMORE, MARYLAND, ASSIGNOR TO THE STROUSE-BAER COMPANY, A CORPORATION OF MARYLAND

DESIGN FOR A GYMNASIUM SUIT

Application filed June 1, 1931. Serial No. 40,035. Term of patent 7 years.

To all whom it may concern:

Be it known that I, ABRAM K. BAER, a citizen of the United States, residing at Baltimore, in the State of Maryland, have invented a new, original, and ornamental Design for a Gymnasium Suit, of which the following is a specification, reference being had to the accompanying drawings, forming a part hereof.

I claim:

The ornamental design for a gymnasium suit, as shown.

ABRAM K. BAER.
